UNITED STATES PATENT OFFICE.

WALTER P. MURPHY, OF CHICAGO, ILLINOIS.

BUFFER-SPRING FOR CAR-VESTIBULE-DIAPHRAGM FACE-PLATES.

1,303,364.

Specification of Letters Patent. Patented May 13, 1919.

Application filed November 16, 1916. Serial No. 131,624.

To all whom it may concern:

Be it known that I, WALTER P. MURPHY, a citizen of the United States, residing at Chicago, in the county of Cook and State of Illinois, have invented certain new and useful Improvements in Buffer-Springs for Car-Vestibule-Diaphragm Face-Plates, of which the following is a specification.

My invention relates to improvements in buffer springs for vestibule diaphragm face-plates and particularly to the general type in which semi-elliptical leaf springs are employed to force the upper part of one face-plate against the face plate of an adjoining vestibule and to return the face plate to its normal position parallel with the end wall of the car after the cars of the train, in rounding a curve, have come back into alignment. It is customary to secure the center portion of these springs to the diaphragm face-plate and to retain the master leaf of the spring in sliding relation with the end wall of the car. It would be possible, though inconvenient and not as desirable, to reverse the position of the springs so that its ends would bear against the face-plate and its middle portion be attached to the end of the car. If some arrangement of this sort is not employed, the friction between the face-plates is likely to prevent them from being returned to their normal position when displaced by a change in the angular position between the cars. In devices of the above character, the engagement of the end or ends of the springs with the retaining means are usually of such a character that a lateral displacement of one face-plate with respect to the other is likely to produce a severe strain of the buffer spring. The vibration of the extremities of such springs against the retaining means is constant, due to movement of the diaphragm plates back and forth, up and down, and sidewise resulting from the inequalities of the road bed and other causes.

These constant vibrations tend to wear down and weaken the spring and also to wear out the retaining devices.

The present invention relates particularly to certain improvements, the purpose of

which is to obviate this somewhat objectionable feature of the original construction.

The invention consists in the new and improved constructions, devices and arrangements to be hereinafter described and claimed, for carrying out the above stated objects and such other incidental objects as will appear from the following description of the invention as embodied in a preferred construction.

The invention is illustrated in the accompanying drawings, wherein—

Figure 1 is a fragmentary plan view of the ends of two railway cars coupled up one to the other, the face-plates of the vestibuled diaphragms of which are furnished with the spring and its attachments constructed in accordance with the present invention;

Fig. 2, a front elevation of one end of the spring showing the retaining means providing the sliding engagement between the end of the spring and the car; and

Fig. 3, a sectional plan on line 3—3 of Fig. 2.

Like characters of reference indicate like parts in the several figures of the drawing.

Referring to the drawing, the numerals 10 designate the end walls of two vestibuled railway cars, the vestibules of which are indicated at 11, 11 and are provided with the usual face-plates 12, 12. The upper portion of each face-plate is engaged by a spring which preferably is a compound, semi-elliptical spring 13 rigidly secured at its middle portion to the face-plate by means indicated generally by numeral 14. My present invention is not concerned with the means by which the center of the spring is secured to the face-plate so that this device need not be described in detail.

On the end wall of the car adjacent each extremity of spring 13 is a retaining bracket 15 provided with outstanding spaced elements 16 between which are arranged a pair of bolts 17 and intermediate these bolts but out of line with them a bolt 18. The bolts 17 are preferably provided with sleeves 19 and the bolt 18 with a sleeve 20, these sleeves forming, in effect, rollers for the end of the master leaf 21 of the spring which extends

between rollers 19 on one side and roller 20 on the other. The end of the spring is preferably bent inwardly between the rollers 19, 19 as shown.

5. To reinforce the extremity of the spring against being weakened by attrition, it is provided with a reinforcing and rubbing element 22 on the side of the spring bearing against rollers 19. Preferably there is a 10 slight clearance between the spring and roller 20 so that this side of the spring does not have as much wear upon it as the side bearing upon rollers 19. Preferably this reinforcing and rubbing element is an integral 15 part of the master leaf of the spring, the end of the spring being bent over and folded down upon itself as shown. At the same time the hook or stop-projection 23 is formed. This stop-projection is adapted to 20 engage with the outer roller 18 when the diaphragm face-plate is displaced to a considerable extent from its normal position. The engagement produces a strain of the spring which tends to return the face-plate to its 25 normal position.

While I have described my invention in certain preferred embodiments, it will be understood that slight and unimportant modifications might be made without departure 30 from the invention. Therefore I do not wish the invention to be considered as limited to the precise constructions and arrangements shown except so far as the claims are so limited.

35. I claim:

1. In combination with the end wall and diaphragm face-plate of a vestibuled railway car, of a leaf spring secured to one of the aforesaid structural elements of the car, 40 and retaining means for the end of the spring arranged on the other of said car elements and comprising rollers arranged on opposite sides of the end of the spring.

2. In combination with the end wall and diaphragm face-plate of a vestibuled railway car, of a leaf spring secured to one of the aforesaid structural elements of the car, and retaining means for the end of the spring arranged on the other of said car elements and comprising a pair of rollers on one side of the spring and a single roller on the other side thereof at a point between the aforesaid rollers.

3. In combination with the end wall and diaphragm face-plate of a vestibuled railway car, of a leaf spring secured to one of the aforesaid structural elements of the car and formed with a stop-projection at its extremity, and retaining means for said extremity of the spring arranged on the other of said car elements and comprising rollers on opposite sides of the spring, one of which is adapted to be engaged by said stop-projection.

4. In combination with the end wall and diaphragm face-plate of a vestibuled railway car, of a leaf spring secured to one of the aforesaid structural elements of the car and formed with a stop-projection at its extremity, and retaining means for said extremity of the spring arranged on the other of said car elements and comprising a pair of rollers on one side of the spring, one of which is adapted to be engaged by said stop-projection and a roller on the other side of the spring at a point between said first named rollers.

5. In combination with the end wall and diaphragm face-plate of a vestibuled railway car, of a leaf spring secured to one of the aforesaid structural elements of the car, and retaining means for the end of the spring arranged on the other of said car elements and comprising a channel-shaped bracket provided with a plurality of rollers between which the end of the spring extends.

6. In combination with the end wall and diaphragm face-plate of a vestibuled railway car, of a leaf spring secured to one of the aforesaid structural elements of the car, and retaining means for the end of the spring arranged on the other of said car elements and comprising a channel-shaped bracket provided with a plurality of rollers between which the end of the spring extends, the latter being formed with a stop-projection to engage one of said rollers.

7. In combination with the end wall and diaphragm face-plate of a vestibuled railway car, of a leaf spring secured to one of the aforesaid structural elements of the car, retaining means on said other car element with which the end of the spring has a sliding bearing, and a reinforcing and rubbing element on the end of the spring engaging said retaining means which is formed integrally with the spring.

8. In combination with the end wall and diaphragm face-plate of a vestibuled railway car, of a leaf spring secured to one of the aforesaid structural elements of the car, and retaining means on said other car element with which the end of the spring has a sliding bearing; the end of the spring being bent over and folded back upon itself to provide a reinforcing and rubbing strip.

9. In combination with the end wall and diaphragm face-plate of a vestibuled railway car, of a leaf spring secured to one of the aforesaid structural elements of the car, and retaining means on said other car element with which the end of the spring has a sliding bearing; the end of the spring being bent over and folded back upon itself to provide a stop-projection and a reinforcing and rubbing strip.

10. In combination with the end wall and

diaphragm face-plate of a vestibuled railway car, of a compound, semi-elliptical leaf spring secured at its middle to the diaphragm face-plate, and retaining devices on the car providing a sliding bearing for the ends of the spring comprising a plurality of

rollers against which the spring bears, the ends of the master leaf of the spring being bent and folded down upon the body of the leaf to reinforce the ends of the spring and provide stop-projections.

WALTER P. MURPHY.
